UNITED STATES PATENT OFFICE.

FRANK RHIND, OF MERIDEN, CONNECTICUT, ASSIGNOR OF ONE-HALF TO
THE EDWARD MILLER & COMPANY, OF SAME PLACE.

ARGAND BURNER.

SPECIFICATION forming part of Letters Patent No. 416,236, dated December 3, 1889.

Application filed March 28, 1889. Serial No. 305,164. (No model.)

To all whom it may concern:

Be it known that I, FRANK RHIND, a citizen of the United States, residing at Meriden, New Haven county, Connecticut, have invented an Improvement in Argand Burners, of which the following is a specification.

My invention relates to Argand lamps, and in part to that class of Argand burners which are integrally detachable from the lamp. It is intended to secure better combustion and more accurate adjustment of the wick.

In the accompanying drawings, Figure 1 represents in elevation a detachable Argand burner embodying my improvements. Fig. 2 is a vertical section of the same. Fig. 3 is a portion of an Argand lamp, showing a modification.

Similar letters refer to like parts in the several views.

20 A designates a burner-body provided at its lower extremity with a screw-threaded portion *a*; A', an outer wick-tube; *a'*, an annular shoulder on the wick-tube A'; B, an inner wick-tube; C, a wick; D, an air port or passage; E, a foraminous skirt; F, a chimney-gallery; f, a chimney-spring; F', a foraminous outer air-distributer; G, a wick-adjusting shaft; *g*, a thumb piece or button and *g'* a cog, both on the shaft G; H, a wick-adjusting band or sleeve; *h*, teeth on the band H; H', a rack attached to the band H; I, an inner air-distributer consisting of sleeve *i*, foraminous shell *i'*, flange *i''*, cone *i'''*, button-shaped shell *i'''*, inner cylinder *i''''*, partition *i'''''*, imperforate cap *i'''''*, and convex dome *i''''''*.

The example of my invention shown in Figs. 1 and 2 of the drawings is constructed and operated as follows: The burner-body A is of convenient size and form, is provided at its lower extremity with an exterior screw-thread *a*, and at its upper end with a screw-thread adapted to engage with the annular flange *a'*. The outer wick-tube A' is provided with a flange *a'*, screw-threaded to engage with the body A. The inner wick-tube B is placed concentrically within the tube A', and is secured at its closed lower end to the bottom of the body A. Through the body A and tube B two openings are cut op-

posite each other, the body A and tube B being in each case united by a wall, thus forming two air ports or passages D. The foraminous skirt E surrounds the body A and is surmounted by the chimney-gallery F. The foraminous outer air-distributer F' is in this instance made integral with the gallery F, and is in the form of a cone-frustum, the least interior diameter of which is slightly greater than the exterior diameter of the tube A'. The wick-adjusting mechanism consists of a shaft G, passing through the body A, ports D D, and skirt E. At the outer end of the shaft G is the ordinary thumb piece or button *g*. Also secured to the shaft G are the cogs *g' g'*, adapted to mesh with the racks H' H'. These racks H' pass upward through openings in the top walls of the ports D, and are secured to opposite sides of the band or sleeve H. This band H is here shown as surrounding the inner tube B, so as to be capable of vertical motion thereon, and provided with exteriorly-projecting teeth *h*, adapted to engage with the wick C.

In Argand burners of this class it has heretofore been customary to provide a shaft with one cog only, adapted to engage with the wick-adjusting sleeve, so that the sleeve was lifted entirely from one side. In this case it is necessary to make the sleeve of a length nearly or quite equal to its diameter to prevent its "sticking" or binding on the wick-tube and to secure an even adjustment of the wick. When a burner is of considerable size, so that large air-ports are necessary, and where it is advantageous to make the burner as short as possible in proportion to its diameter, such a length of wick-adjusting sleeve is impracticable. In large burners, therefore, the advantage of providing two racks at opposite sides of the wick-adjusting band or sleeve and two cogs on the shaft adapted to engage with said racks will be most apparent.

The inner air-distributer I, as here shown, is formed with a sleeve *i* of an exterior diameter slightly less than the interior diameter of the inner wick-tube B and adapted to pass into said tube. Below the sleeve *i* is an in-

verted conoidal foraminous shell i' , and above or within the sleeve is the interiorly-projecting annular flange i^2 , perforated with holes considerably larger than those in the other 5 portions of the distributor I. Rising from the inner edge of the flange i^2 is the foraminous cone-frustum i^3 , surmounted by the foraminous button-shaped portion i^4 . The top of the distributor I is closed by an imperforate cap i^5 , (here shown as dish-shaped,) projecting beyond the perforate portion at its lower edge and flaring outwardly. Above the cap i^5 is the convex shell or dome i^8 , which may be secured to the cap in any convenient 15 manner. Within the perforated portions named is the foraminous cylinder i^6 , of a diameter substantially equal to the least diameter of the shell i^4 and extending downward to the bottom of the distributor I. Extending 20 diametrically across the cylinder i^6 is the partition i^9 , which may be conveniently suspended from the lower side of the cap i^5 . It may, however, be secured to or made integral with the cylinder i^6 . Its office is to check 25 the tendency of the air in the distributor to rise in a spiral current. I have here shown it as perforated, so as to interfere as little as possible with the equal distribution of air to the flame in case the supply entering one of 30 the ports D should at any time be greater than that drawn in at the other.

It will be seen that all the air required to support combustion passes through the foraminous skirt E and through at least one 35 other perforate shell. The air which supplies the outer surface of the flame after passing through the skirt E is carried up around the burner-body A and through the foraminous cone-frustum F'. It is thus admitted 40 freely to the space between the flame and the chimney, no conoidal deflector being required to cause it to impinge against the flame. The burner is kept much cooler and the air is delivered to the flame more evenly 45 along its entire height, so that a much higher flame can be produced than where an outer deflector is employed. The air introduced to the interior surface of the flame after passing through the skirt E and the ports D is 50 carried upward and through the perforate shells which constitute the distributor I. It will be seen that the larger perforations in the flange i^2 provide the base of the flame with a free supply of air, which, however, has 55 been "strained" or divided by passing through the shell i' or the cylinder i^6 . By making the cap i^5 dish-shaped, as shown, I produce a higher and less serrated flame than with the flat thin cap in ordinary use. In practice, 60 however, I have found that eddies of air are formed within the dish-shaped cap, which interfere with the steadiness of the flame. To obviate this I provide the dome or convex shell i^8 .

65 In Fig. 3 is shown part of the permanent central air-supply tube which passes through

the fount of an ordinary Argand lamp. In this case the distributor I is shown as a foraminous cylinder partly within the tube B and supported by a bead formed near the 70 upper end of said tube. In this case the cap i^5 and the convex portion i^8 are shown as integral. In this case also the partition i^9 is shown as imperforate, as in this class of lamps, while the tendency of the air to rise 75 in a helical current still exists, there is less danger of its being diverted to one side of the distributor only.

It is evident that many mechanical changes 80 may be made without departing from my invention, and that I do not consider myself limited to the particular forms of construction shown or described.

As United States Letters Patent have previously been issued on my applications for an 85 inner air-distributer consisting of a foraminous cone-frustum surmounted by a button-shaped portion, also perforated, and for an air-distributer consisting of two perforated shells, one within the other, said patents being numbered 333,338 and 382,270, respectively, I do not herein claim anything described or claimed in either of said patents.

What I claim as my present invention, and desire to secure by Letters Patent of the 95 United States, is as follows:

1. In an Argand burner, the combination of a wick-adjusting band, two racks secured to said band, and two pinions or cogs adapted to engage with said racks and attached to a single 100 shaft, substantially as described.

2. In an Argand burner, a wick-adjusting device consisting of a shaft, a thumb piece or button on said shaft, two cogs or pinions, also on said shaft, two racks adapted to engage 105 with said pinions, and a wick-adjusting band to the opposite sides of which said racks are attached, substantially as described.

3. In the inner air-distributer of an Argand lamp, the combination of a lower foraminous 110 portion and an annular flange above and perforated with larger holes than said lower foraminous portion, and adapted to supply to the lower inner surface of the flame air which has previously passed through said lower foraminous portion, substantially as described.

4. In the inner air-distributer of an Argand lamp, the combination, with the perforate walls, of a diametric partition, substantially as described.

5. In the inner air-distributer of an Argand lamp, the combination, with the perforate walls, of a foraminous diametric partition, substantially as described.

6. In the inner air-distributer of an Argand lamp, the combination of a foraminous portion, an imperforate dish-shaped cap covering said foraminous portion, and a convex or dome-shaped portion integral with or secured to said cap, substantially as described.

7. In the inner air-distributer of an Argand lamp, the combination of a foraminous cone-

frustum surmounted by a foraminous button-shaped portion, and a cap covering and extending beyond the outer edge of said button-shaped portion and provided with a convex or dome-shaped upper surface, substantially as described.

8. In the inner air-distributer of an Argand lamp, the combination of foraminous portions,

as follows: shell i' , flange i^2 , cone i^3 , button-shaped portion i^4 , and inner cylinder i^5 , substantially as described.

FRANK RHIND.
